(57) **CLAIM**

The ornamental design for a hobby knife with retractable blade, as shown and described.

DESCRIPTION

FIG. 1 is a front perspective view of a hobby knife with the blade partially extended from the handle showing the design; FIG. 2 is a side elevation view thereof:

FIG. 3 is an opposite side elevation view thereof;

FIG. 4 is a top elevation view thereof;

FIG. 5 is a bottom elevation view thereof;

FIG. 6 is a rear elevation view thereof;

FIG. 7 is a front elevation view thereof;

FIG. 8 is a front perspective view of the hobby knife with the blade completely extended; and,

FIG. 9 is a front perspective view of the hobby knife with the blade completely retracted.

The features illustrated in broken line form are provided for purposes of environment and form no part of the claimed design.
